H. G. GILLMOR.
ANTICREEPER FOR RAILWAY RAILS.
APPLICATION FILED FEB. 17, 1915.

1,240,843.

Patented Sept. 25, 1917.

UNITED STATES PATENT OFFICE.

HORATIO G. GILLMOR, OF WASHINGTON, DISTRICT OF COLUMBIA.

ANTICREEPER FOR RAILWAY-RAILS.

1,240,843.

Specification of Letters Patent. Patented Sept. 25, 1917.

Application filed February 17, 1915. Serial No. 8,860.

To all whom it may concern:

Be it known that I, HORATIO G. GILLMOR, of Washington, in the District of Columbia, have invented a new and useful Improvement in Anticreepers for Railway-Rails, of which the following is a specification, accompanied by drawings.

This invention relates to a device known as anticreepers or rail anchors, and one of its objects is to form a simple and inexpensive device which will prevent longitudinal movement of the rails of railways.

Another object of the invention is to provide for the automatic tightening of the grip of the device upon the rail when the rail is subjected to stresses tending to produce such longitudinal movement.

Other objects are to provide an anticreeper having improved means for locking it in position, which will not work loose after being applied but which may be readily removed if desired and to provide an anticreeper which operates with the maximum of efficiency under all conditions.

In the accompanying drawing, I have illustrated a preferred form of the invention in which:

Figure 1 is a sectional view of the anticreeper; Fig. 2 a view showing positions of the parts when the vertical pressure producing part is being forced into position; Fig. 3 is a view of the device as seen from below the rail; Fig. 4 a side elevation of the device applied to the rail; and Fig. 5 a view illustrating a manner of removing the vertical pressure producing part from the rail.

Similar letters apply to similar parts throughout the several views.

In the embodiment of the invention illustrated in the drawings A is the rail, B a transverse rail engaging member and C a vertical pressure producing member. The part B is constructed with one or more shoulders D adapted to bear upon the edge of the base flange of the rail at one side of the rail and a hook portion E which forms a jaw adapted to engage the base flange of the rail at the other side. E and D are so arranged that the part B may be applied transversely to the rail from one side with E engaging the upper surface of the base flange of the rail and D engaging the edge of the opposite base flange, about as illustrated in Fig. 2. The part B is constructed with a groove F on its under side. The bottom of this groove is a plane surface for the portion G and curved surface for the portion H. The body portion of the part B has relatively light transversely extending sides I and K which are connected by a web L, a rib or 60 partition M, and endpiece N upon which are formed the shoulders D and an end piece O upon which is formed the hook E. The side piece K is offset for a portion of its length near the middle and projects downwardly to form the tie-abutting portion P arranged to engage the tie Q. The upper edges of the sides I and K are preferably so formed that the portions R and S are at a small angle to one another and meet at 70 about T. The vertical pressure producing part C has an arm U constructed to engage the upper surface of the rail base flange and an arm V, having at W curved surfaces corresponding to the curved surface H at the 75 bottom of the groove F and a plane surface X corresponding to the plane surface G of the bottom of the groove F.

The device is applied by placing the part B transversely below the rail with the hook 80 E engaging the upper surface of the base flange at one side and forcing this part on to the rail until the inside of the shoulders D will engage the opposite edge of the rail base. The part C is then placed with the 85 arm U engaging the upper surface of the rail base flange opposite to the hook E and the curved surface W of the arm V engaging the plane surface G of the bottom of the groove F in the part B. The part C is 90 then forced, preferably by driving with a hammer or maul, transversely in relation to the rail and the part B which action draws the part B upward with the shoulders D in contact with the edge of the rail base. The 95 sides I and K of the part B are angled at T and in drawing the end of B upwardly as C is forced transversely the part B fulcrums at T and a strong upward pressure is exerted with a corresponding downward 100 pressure of the hook E and the part C upon the upper surfaces of the rail base flange. The relative positions of the parts at one point in this application of the device is shown in Fig. 2. As the part C is forced 105 farther on to the rail and the part B the curved surfaces W of the arm V come into engagement with the curved surface H at the bottom of the groove F in B. The elasticity of the parts C and B then permits the 110 plane surface X of the arm V to engage the plane surface G of the bottom of the groove

F. The groove in B serves to guide the arm V and hold the part C transverse to the rail while the part C is being driven into place. The position of the parts after the 5 part C has been driven into place is shown in Fig. 1 and it will be seen that in this position the parts are locked against transverse movement in relation to the rail and to each other by the engagement of the curved part 10 W of the arm V with the curved part H of the bottom of the groove in the part B. In this final position the transversely extending part B is firmly gripping one side and the bottom of the rail base flange and bears 15 upon the edge of the opposite side of the base flange and the part C is firmly pressing the upper surface of the base flange of the rail. The arrow in Fig. 4 indicates the direction in which the rail tends to creep. It 20 will readily be understood that the engagement of the tie abutting portion P of the part B with the tie Q will hold the rail against any creeping action so long as the tie is held in position and the grip of the 25 part upon the rail is sufficient. Generally the gripping action produced by applying the parts as described will be sufficient. Should there be, however, not sufficient grip of the device initially upon the rail the rail 30 will move forward slightly in the direction of the arrow and will carry with it, in the movement, the arm U of the vertical pressure producing part C and this part C will take up a position indicated by the dotted 35 lines in Fig. 4. This action will automatically increase the grip of the device upon the rail and a very small movement of the rail in relation to the part B will so increase the grip of the device as to effectually prevent 40 further movement.

The parts C and B are automatically locked in position when C is finally driven into position by the engagement of the curved portion W of the arm V forming 45 part of the part C with the curved portion of the bottom of the groove F in the part B. If it be desired to remove the device from the rail, however, the arm U may be forced back by driving with a hammer or 50 maul and if this is done the part C will move angularly and assume a position such as shown in Fig. 5. The surfaces H and W are so constructed and arranged in relation to the parts B and the arm U of the part C 55 that the driving back of the arm U will cause angular movement of the part C in relation to the part B and release C so that it may be removed and then by bearing the end of the part B down until the shoulders 60 D no longer engage the rail edge the part B may be forced transversely until the hook E no longer engages the rail base.

It is obvious that various changes may be made in the structure described, without departing from the spirit of the invention. I 65

desire, therefore, to cover in the appended claims whatever modified structures fall within the scope of the invention.

Having thus described my invention, what I claim as new and desire to secure by Let- 70 ters Patent is:

1. A part for rail anchors constructed with a rail base flange engaging jaw at one end, a retaining catch at the other end, and a body portion having a downward inclination toward the retaining catch end thereof and a seat in the under side of the part at the retaining catch end thereof. 75

2. A rail gripping element constructed with a jaw at one end and a plurality of 80 base edge engaging catches at the other end and a body portion, the upper surfaces of which are in two planes, that toward the catches inclining downwardly from that toward the jaw and a groove seat for engagement with a vertical pressure producing 85 part.

3. A rail embracing and gripping element constructed with a rail base engaging jaw at one end, a retaining portion at the other 90 end and a body provided with a tie engaging portion intermediate of said jaw and said retaining portion, the upper surfaces of said body portion being downwardly inclined from the jaw toward the retaining 95 portion end thereof.

4. A rail gripping element constructed with a groove in the under side thereof, the bottom of the groove having a plane surface and a curved surface adapted to engage 100 with a vertical pressure producing part.

5. A rail embracing and gripping element constructed with a rail base flange engaging jaw and a transverse portion having upper surfaces in two planes lying at a relatively 105 small angle the one to the other and a seat adapted to engage with a vertical pressure producing part at the end opposite to said jaw.

6. A rail base gripping element constructed with a base flange gripping jaw at one end of a rail base edge engaging portion at the other end thereof and a seat, transverse to the rail, in the under side of said element 115 adapted to engage with a vertical pressure producing part.

7. An anticerper for railroad rails comprising a rail gripping element having a downward inclination, a jaw at one end and a retaining catch at the other end of said element, and a rail engaging device for drawing the downwardly inclined element into contact with the rail bottom and said retaining catch into engagement with the rail base edge. 120

8. A device for preventing the creeping of rails comprising a rail gripping element having a downward inclination, a jaw at one end and a retaining catch at the other end of said element, a rail engaging part 125 130

for drawing the downwardly inclined element into contact with the rail bottom and said retaining catch into engagement with the rail base edge and means for giving said device a fixed position in the roadbed in opposition to the tendency of the rail to creep.

9. A vertical pressure producing part constructed with two arms adapted to engage the upper surface of the rail base flange and a groove in the bottom of a rail base engaging member and so arranged that when said part is driven transversely onto the rail and into engagement with the base engaging member it is automatically locked by the engagement of surfaces of one of said arms with surfaces of said base engaging member.

10. An anticreeper for rails, comprising a rail gripping element constructed with a groove in the under side thereof, transverse to the rail, having a plane surface and a curved surface and a part engaging the rail and the plane surface and the curved surface of said groove in succession for effecting the gripping action and automatically locking the parts.

11. A device for preventing the creeping of rails comprising a rail gripping element embracing the rail base flange at one side of the rail and constructed with a catch projection adapted to engage the rail base flange at the other side of the rail, said element being normally inclined downwardly from the rail bottom and a rail engaging part constructed to engage said element for drawing said catch projection into contact with the rail base edge.

12. A rail anchor comprising a rail gripping element embracing the base flange at one side of the rail and provided with a catch projection adapted to engage the rail base flange at the other side of the rail and with a tie engaging portion, said element being normally inclined downwardly from the rail bottom, and a rail engaging device engaging said element for drawing the catch projection into contact with the edge of the rail base flange.

13. An anticreeping device for rails, comprising a rail engaging and gripping element constructed with a tie-engaging portion and a groove in the under side thereof having plane and curved surfaces and a rail engaging part constructed to engage said plane and curved surfaces in succession for effecting the gripping action of the device.

14. A device for preventing the creeping of rails comprising a gripping member transversely disposed in relation to the rail provided with a rail base flange gripping portion at one end and a rail base edge engaging portion at the other end thereof, a pressure producing part engaging the rail base above and said gripping member below the rail and means for giving the device a

fixed position in the roadbed as against the tendency of the rail to creep.

15. An anticreeper, comprising a gripping member for transverse disposition beneath the rail and provided with a rail base flange 70 gripping portion at one end and a base edge engaging portion at the other end thereof and a vertical pressure producing part arranged to engage the rail base flange above and said gripping member below the rail. 75

16. In an anticreeping device for rails a rail engaging and gripping element arranged to engage the top of the base flange and to fulcrum upon the bottom of the base flange at one side of the rail and a rail engaging device constructed to engage said gripping element at the opposite side of the rail to effect the gripping action. 80

17. An anticreeping device for rails, comprising a rail embracing and clamping element arranged to engage the base flange at one side of the rail and extend transversely beneath the rail with a downward inclination and a transversely disposed vertical pressure producing part pivotally connected 85 to said element. 90

18. In an anticreeping device for rails, a tie-engaging rail gripping element having a downward inclination arranged for transverse disposition beneath the rail and a 95 transversely arranged device having hinging engagement with said element for effecting the gripping action.

19. An anticreeping device, comprising a rail engaging element for transverse disposition beneath the rail engaging at one side of the rail the upper surface of the base flange and at the other side of the rail the edge of the base flange and a part engaging the rail base above and said element below 100 the rail and arranged to be moved transversely in relation to the rail for placing in position and effecting the gripping action. 105

20. An anticreeper for rails comprising a bottom engaging part and a vertical pressure producing part constructed so to engage said bottom engaging part below the rail that movement of said pressure producing part transversely in relation to the rail will produce pressure of said bottom engaging part upon the bottom of the rail and that longitudinal movement of the rail in relation to said bottom engaging part will produce angular movement of said vertical pressure producing part and thereby automatically increase the gripping action 110 upon the rail. 115

21. An anticreeping device comprising a rail embracing element constructed to engage the top and bottom of the base of a rail at one side of the rail and the edge of the base flange at the other side thereof and a vertical pressure producing part arranged to engage the base flange above and the rail embracing element below the rail. 120 125 130

22. A device for preventing the creeping of rails comprising a rail engaging and gripping element constructed to engage the top of the base of the rail at one side and the 5 edge of the base of the rail at the other side of the rail and to fulcrum upon the bottom of the rail base, a rail engaging part constructed to engage said gripping element below the rail to effect the gripping action, 10 and means for giving the device a fixed position in the roadbed in opposition to the tendency of the rail to creep.

23. A rail anchor comprising a rail engaging and gripping element constructed to 15 engage the top of the base flange and to fulcrum upon the bottom of the base flange at one side of the rail, a rail engaging device constructed to engage said gripping element at the other side of the rail for effecting the 20 gripping action, and means for engaging a fixed portion of the roadbed in opposition to the tendency of the rail to creep.

24. An anticreeping device comprising a rail engaging element transversely disposed 25 beneath the rail in engagement at one side of the rail with the upper surface of the base flange and at the other side of the rail with the edge of the base flange and provided with a portion adapted to engage a fixed 30 portion of the roadbed and a part engaging the rail base above and said element below the rail and arranged to be moved transversely in relation to the rail for placing said part in position and effecting the 35 gripping action.

25. A rail stay comprising an element engaging the bottom and opposite sides of the rail base and provided with means for engaging a fixed portion of the roadbed and 40 a pressure producing part constructed so to engage said element below the rail and the upper surface of the base of the rail that movement of said part transversely in relation to the rail will produce pressure of 45 said element upon the rail and that longitudinal movement of the rail in relation to said element will produce angular movement of said pressure producing part and thereby automatically increase the gripping 50 action upon the rail.

26. A device for preventing the creeping of rails comprising a rail embracing element constructed to engage the bottom of the rail and a fixed portion of the roadbed, the top 55 of the base flange at one side and the edge of the base flange at the other side of the rail, and a pressure producing part constructed to engage the base flange above and said element below the rail.

60 27. A rail anchor comprising a rail base engaging part constructed with a jaw at one end, a base edge engaging portion at the other end, an intermediate tie-engaging portion, and bearing surfaces; and a rail base engaging, pressure producing element con-

structed with bearing surfaces so coating with those of said part that transverse movement of said part will effect a cam action and gripping of the rail by said device.

28. A rail anchor comprising a rail base 70 engaging part constructed with portions for engagement with opposite sides of the rail base and bearing surfaces, a rail base engaging, pressure producing element constructed with bearing surfaces so coating 75 with the bearing surfaces of said part that transverse movement of said element will effect a cam action and gripping of the rail, and means for giving said anchor a fixed position in the roadbed in opposition to the 80 tendency of the rail to creep.

29. A device for preventing the creeping of rails comprising a rail gripping bottom engaging element provided with means for engaging the rail base at opposite sides of 85 the rail, a transversely movable rail engaging part engaging said element below and the rail base above the rail bottom for pressing said element against the rail base and effecting the gripping action of the device 90 and means for engaging a fixed portion of the roadbed.

30. An anticreeper comprising a tie engaging, rail gripping element, having a downward inclination, transversely disposed 95 beneath the rail and provided with means for engaging the rail base edge at one side, and a transversely movable rail engaging part engaging said element below the rail for drawing the downwardly inclined element 100 up into contact with the rail bottom.

31. A device for preventing the creeping of rails comprising an element embracing the rail base at one side of the rail and engaging the edge of the rail base at the 105 other side of the rail and a part embracing the rail base and the rail base edge engaging end of said element and gripping the rail base between said part and said element.

32. A rail anchor comprising an element 110 embracing the rail base at one side of the rail, extending transversely beneath the rail with a tie-engaging portion and engaging the edge of the rail at the other side of the rail, and a part embracing the rail base and the rail base edge engaging end of said 115 element and gripping the rail base between said part and said element.

33. An anticreeper comprising an element embracing one side of the rail base and 120 engaging the edge of the other side of the rail base and a part embracing the rail base and the rail base edge engaging end of said element and pivotally engaging said element for effecting the gripping action.

34. A device for preventing the creeping of rails comprising an element engaging one edge of the rail base, extending transversely underneath the rail and embracing the rail base at the other side of the rail, a part 130

embracing the rail base and the rail base edge engaging end of said element and pivotally engaging said element for effecting the gripping action of the device, and 5 means for engaging a fixed portion of the roadbed.

35. A rail anchor comprising two rail gripping elements, one of which is formed with a tie engaging portion, engages the rail 10 base at one side of the rail, extends transversely beneath the rail and engages the edge of the rail base at the other side of the rail, and the other of which element comprises a member which engages the first 15 named element and the upper surface of the rail base and is forced into position by transverse movement in relation to the rail.
36. A device for preventing the creeping of rails comprising two rail gripping members, one of which is formed to engage a 20 fixed portion of the roadbed in opposition to the tendency of the rail to creep, and comprises a transverse element engaging the rail base at opposite sides of the rail, 25 and the other a clamp engaging the rail

base above and said element below the rail to draw and hold said element against the rail base.

37. A device for preventing the creeping of rails comprising two rail gripping elements, one of which is formed with means 30 for engaging a fixed portion of the roadbed in opposition to the tendency of the rails to creep and has a jaw engaging the rail base at one side and a portion engaging the edge 35 of the rail base at the other side of the rail, and one of which comprises means for bearing upon the top of the rail base and engaging the other element to draw and hold said element with said base edge engaging portion in engagement with the edge of the rail base. 40

In testimony whereof, I have signed my name to this specification in the presence of two subscribing witnesses.

H. G. GILLMOR.

Witnesses:

It is hereby certified that in Letters Patent No. 1,240,843, granted September 25, 1917, upon the application of Horatio G. Gillmor, of Washington, District of Columbia, for an improvement in "Anticreepers for Railway-Rails," an error appears in the printed specification requiring correction as follows: Page 2, line 112, claim 6, strike out the word "of"; and that the said Letters Patent should be read with this correction therein that the same may conform to the record of the case in the Patent Office.

Signed and sealed this 28th day of January, A. D., 1919.

[SEAL.]

R. E. WHITEHEAD,

Acting Commissioner of Patents.
